UNITED STATES PATENT OFFICE.

JOHN KLEGER, OF MARSHLAND, OREGON, ASSIGNOR OF ONE-HALF TO C. H. STOCKWELL,
JR., OF CLATSCHANIE, OREGON.

MAILING-TUBE.

1,153,627.

Specification of Letters Patent. Patented Sept. 14, 1915.

Application filed April 9, 1914. Serial No. 830,735.

To all whom it may concern:

Be it known that I, JOHN KLEGER, citizen of the United States, residing at Marshland, in the county of Columbia and State 5 of Oregon, have invented certain new and useful Improvements in Mailing-Tubes, of which the following is a specification.

This invention relates to mailing tubes or wrappers, and has for one of its objects to 10 provide an inexpensive article of this character which may be readily adapted to the size of the article to be mailed and in which provision is made for protecting the contents of the wrapper from injury and likewise to 15 prevent the escape of the article from the inclosure during transit.

Another object of the invention is to provide a simply constructed device which may be shipped in quantities "knocked down" or 20 flat form.

Another object of the invention is to provide a simply constructed device including a 25 protecting casing or wrapper which is readily adaptable to the size of the article to be mailed, an inner wrapper or envelop, and an external wrapper or casing so arranged that the various portions strengthen and support each other.

With these and other objects in view the 30 invention consists in certain novel features of construction as hereinafter shown and described and then specifically pointed out in the claim: and in the drawings illustrative of the preferred embodiment of the invention. Figure 1 is a view of the improved device in its flat or open form. Fig. 2 is an 35 enlarged detail in section on the line 2—2 of Fig. 1. Fig. 3 is a perspective view of the improved device in its closed form in condition for mailing. Fig. 4 is a transverse section on the line 4—4 of Fig. 3.

Corresponding and like parts are referred to in the following description and indicated in all the views of the drawings by the same 45 reference characters.

The improved device comprises three portions, a main body portion which forms the protecting casing of the package of relatively heavy cardboard, an envelop-like portion 50 preferably attached to the inner face of the body and designed to contain the article to be mailed, and an outer wrapper or casing attached to the outer face of the body and adapted to be wrapped around the body 55 after the latter has been rolled around the

article to be mailed. The body portion of the improved device is represented as a whole at 10 and is greater in length than the article to be mailed and sufficiently wide to enable the body to be rolled around the 60 mailed article with the edges overlapping to a sufficient extent to afford the necessary protection to the mailed article. The body may be of any required width to enable the edges to be overlapped to any required extent, and one edge will be chamfered or reduced, as represented in Fig. 2 at 11, the object to be hereafter explained.

An envelop-like device is attached to the inner face of the body 10, preferably near 70 the edge farthest from the chamfered edge 11, and includes a body portion 12, side flaps 13—14 and end flaps 15—16, the various flaps adapted to be folded inwardly in superimposed relation with each other and 75 with the body 12 and thus form an envelop or wrapper in which the article to be mailed is inclosed. The body 12 of the envelop member is cemented or otherwise secured as indicated at 17 to the body 10.

Secured to the body 10, preferably by pasting, is a strip of material to constitute the exterior wrapper of the improved device and preferably formed of tough readily foldable paper and represented as a whole 85 at 18. The member 18 is considerably longer than the body 10 and projects beyond the ends of the same, the projecting portions forming the closures for the ends of the protruding casing or tube as the latter is rolled 90 around the article to be mailed as hereafter explained.

With a device thus constructed when an article is to be mailed, it is deposited upon the body 12 of the envelop and the various 95 flaps 13—14—15—16 folded inwardly in superimposed relation and thus form an envelop or wrapper which entirely incloses the article to be mailed. The various flaps may be folded in any desired order, but generally 100 the flap 14 will first be folded then the end flaps 15—16 folded over the folded flap 14, and the flap 13 folded over the folded flaps 15—16. If preferred, the last flap to be 105 folded, as for instance the flap 13, may be provided with an adhesive indicated at 20 to secure the contents of the envelop after the various flaps have been folded. The body 10, which as before stated, is constructed 110 of relatively heavy cardboard material,

is then rolled around the folded envelop member with its inclosure to transform the body 10 into a tube corresponding in diameter to the envelop and its contents. The 5 member 18 is then wrapped around the tube-like structure thus formed and the end projections tucked into the ends of the tubular member as represented in Fig. 3. The free edge of the member 18 may be provided 10 with an adhesive represented at 21 and after the member 18 has been wrapped around the rolled member 10 and the ends tucked in, the adhesive 21 may be moistened and secured to the outer surface of the wrapper 15 as will be obvious. By this means the tubular-like member is effectually secured in its tubular form and the contents amply protected from injury or from displacement from the closure. The reduced edge 11 enables 20 the tube to be formed without producing an objectionable ridge or protuberance in the wrapper member 18 when the latter incloses the tube, and is therefore an important feature of the device. The inner envelop 25 member is also an important feature of applicant's device and adds materially to its value and efficiency, as the article which is to be mailed is thoroughly protected and prevented from displacement. By employing 30 the envelop-like structure, small articles such as seeds and the like, may be safely mailed or otherwise shipped without danger of loss.

The improved device is simple in construction, can be manufactured of any required size and any required proportions to adapt it to the nature or form of the matter to be mailed. The various members may be 35 of water-proof material and thus provide ample protection to the contents of the envelop from moisture, and likewise protect

contiguous mailing matter from contact with the contents of the envelop. By this means articles which would otherwise be non-mailable may be safely mailed without 45 danger of injury to other mail matter.

Having thus described the invention, what is claimed as new is:

A mailing receptacle including an oblong body capable of being rolled into tubular form, an envelop device carried by the body, the said envelop device including a substantially rectangular body portion secured intermediate its ends to the body adjacent one end thereof, the said body having its opposite extremities free and providing side flaps, and laterally extending flaps projecting from the longitudinal side edges of the said body portion substantially midway the ends thereof and contiguous to the adjacent end 55 of the said first mentioned body, the said last mentioned flaps being of a width less than the length of the body portion of the envelop device and being adapted to coact with each other and with said first mentioned flaps to completely inclose the article to be mailed, and a substantially rectangular wrapper carried by the extremity of the body opposite the envelop device, the said body being 60 connected substantially midway its ends to one longitudinal edge of the wrapper with the wrapper normally projecting laterally beyond the adjacent end of the body, the wrapper being of a length considerably 65 greater than the width of the body. 70

In testimony whereof I affix my signature in presence of two witnesses.

JOHN KLEGER. [L. S.]
